CARBURETION

Frank C. Mock and Emil O. Wirth, South Bend,
Ind., assignors to Bendix Aviation Corporation,
South Bend, Ind., a corporation of Delaware

Application August 3, 1940, Serial No. 350,516

7 Claims. (Cl. 123—119)

This invention relates generally to carburetors and more particularly to improvements in induction passages for multiple venturi carburetors.

In many multi-cylinder internal combustion engines, the intake manifold distributes and delivers the fuel mixture unevenly among the various cylinders. This uneven distribution of fuel mixture by the intake manifold causes some cylinders to receive a richer mixture than others resulting in well known operating faults such as excessive fuel consumption, decrease in power, and in extreme cases, uneven running of the engine.

An engine assembly includes a number of variables that affect the mixture distribution to the cylinders, among which are: the order of firing, the valve timing, valve overlap, intake manifold design and the carburetor. Any one of these factors may cause uneven distribution of the mixture or several or all of them may collectively contribute thereto. Heretofore, correction of the respective factors individually has generally been extremely difficult as it is not always possible to determine to what extent each factor contributes to the uneven mixture delivery. However, it has been discovered that the problem can be solved by modifying the induction passage of the carburetor to deliver fuel mixture asymmetrically to the inlet of the intake manifold to compensate for all of the factors, taken collectively, causing uneven distribution. It is therefore an important object of the invention to provide a carburetor having an induction passage that will supply an asymmetrical fuel mixture to the intake manifold to correct errors of mixture distribution.

In multiple venturi carburetors, the position of the several venturis relative to each other and to the throttle barrel or mixture outlet largely governs the axis of the fuel spray relative to the air column in the induction passage and it has been found that by offsetting one of these parts relative to the others an asymmetrical fuel spray is produced which provides the desired asymmetrical mixture delivery to the inlet of the intake manifold.

It is, therefore, another important object of the invention to provide a carburetor of this character wherein at least one of the component parts of the induction passage which govern the axis of the fuel spray is offset relative to the other parts whereby asymmetrical fuel mixture delivery to the intake manifold is effected.

It is still another object of the invention to provide a device of this character wherein at least the outlet of an element or part of the induction passage is offset with respect to the other elements.

Other objects and advantages of the invention will appear from the following detailed description taken in connection with the accompanying drawings, in which:

Figure 1 is a vertical section through a carburetor embodying the invention;

Figure 2 is a partial plan view of an intake manifold attached to an engine block and adapted to have a downdraft carburetor attached thereto; said view includes the forward end of the manifold;

Figure 3 is a partial horizontal section through the induction passage above the large venturi showing a modified embodiment of the invention;

Figure 4 is a partial vertical section through a carburetor induction passage showing another modification of the invention; and

Figure 5 is a similar view taken at right angles relative to the views shown in Figures 1, 3 and 4 and showing another modification of the invention.

Referring more particularly to Figures 1 and 2, there is shown a double venturi downdraft carburetor having an air horn section 10, a main body section 12, and a throttle body section 14 having a flange 16 attached to an intake manifold 17 by bolts 18, said manifold having its outlets 21 attached in the usual manner to block 23 of an engine. The carburetor induction passage comprises an air inlet 18 controlled by an offset choke valve 20 mounted on a shaft 22 and controlled by any suitable manual or automatic means, a small or primary venturi 24, a large or secondary venturi 26, a throttle barrel or mixing chamber 28, and a mixture outlet 30. A throttle valve 32, mounted on throttle shaft 34, controls the throttle barrel in the known manner.

A fuel chamber 36 in the main body section has the usual float 38 mounted by any known means (not shown) for controlling the level L—L of fuel in the chamber. Idling jet 40 of known construction is supplied with idling fuel from chamber 36 by means of communicating passages 42, 44 and 46, the latter having the usual idling tube 48 therein. The lower end of passage 46 communicates with an acceleration well 50 formed in the usual manner by an enlargement 55 of the bore in which a tubular main fuel nozzle

52 of known construction and operation is received. The main fuel nozzle 52 is positioned toward the forward end of the engine, and is secured in the bore by a plug 54 screwed into a boss formed integral with a wall of the main body section 12. The plug is provided with a metering orifice 56 receiving fuel from the lower part of fuel chamber 36. Air is bled to the nozzle 52 from an air bleed 68 in the known manner. In the embodiment of the invention disclosed in Figure 1, the small venturi 24 and throttle barrel 28 are concentric having a common axis A—A which is also the axis of the mixture inlet 61 of the manifold 17. To produce an asymmetrical fuel spray in the induction passage and deliver same asymmetrically to the inlet 61, the large venturi 28 is offset, its axis B being illustrated as to the right or rear of axis A—A in Figure 2. The air inlet passage 18 is also concentric with the small venturi and throttle barrel but this passage has little effect on the symmetry of the fuel mixture in the carburetor.

In Figure 3, the large venturi 28 is also offset from a concentric venturi and throttle barrel but the position of the axis of the large venturi is modified, being indicated at C, said axis C being diagonally rearward of axis A and away from the engine block.

In the modified embodiment of the invention shown in Figure 4, similar parts are given the same reference numerals as those in Figure 1 plus 100, the air inlet passage 118, the primary venturi 124 and the secondary venturi 128 being concentric with a common axis A₁—A₁. In this embodiment of the invention, the throttle barrel is offset, the axis being indicated at T—T.

In the modification illustrated by Figure 5, similar parts are given the same reference numerals as in Figure 1 plus 200. The air inlet 218, large venturi 228 and throttle barrel 228 are concentric with respect to common axis A₂—A₂. In this embodiment, the small venturi 224 is laterally or transversely offset, its axis being at S—S, as shown also in Figure 2.

While the invention has been shown in connection with a double venturi down draft carburetor, it is to be understood that it may also be embodied in other types including updraft or horizontal draft carburetors or those having more than two venturis. The offsetting of the fuel spray may be made in any direction or of any degree in the induction passage that will provide the desired asymmetrical fuel mixture to the inlet 61 which will correct errors of mixture distribution to the engine cylinders. It is also to be understood that while the various parts of the induction passage that determine the axis of the fuel spray are shown in the various figures as being axially offset, the offsetting of the outlet of one of these parts, such for example as by tilting the small venturi relative to the axis of the large venturi, will also produce a suitable asymmetrical fuel mixture.

It is thought that the invention and many of

its attendant advantages will be understood from the foregoing description, and it will be apparent that various changes may be made in the form, construction and arrangement of the parts without departing from the spirit and scope of the invention or sacrificing all of its material advantages, the forms hereinbefore described being merely preferred embodiments thereof.

We claim:

- 10 1. In a downdraft carburetor, an induction passage having a concentric air inlet, primary venturi, and throttle barrel, and a secondary venturi axially offset relative thereto, the section of the induction passage containing the venturis being of constant effective area.
- 15 2. In a carburetor, an induction passage having an air inlet, a primary venturi, a secondary venturi, and a mixture passage, the section of the induction passage containing said venturis being of constant effective area, and a fuel nozzle to deliver fuel to the primary venturi, the primary venturi and mixture passage being concentric and the secondary venturi being offset relative thereto.
- 20 3. In a charge forming device having an induction passage including a primary venturi, a secondary venturi, and a mixing chamber, the section of the induction passage in which the venturis are disposed being of constant effective area, and means to deliver fuel to one of the venturis, the primary venturi and mixing chamber being concentric, the secondary venturi having its outlet eccentric relative to the primary venturi and mixing chamber.
- 25 4. In an induction passage for a charge forming device, a small venturi, a mixing chamber coaxial therewith, and a large venturi offset relative to said small venturi and mixing chamber, the section of the induction passage in which the venturis are located being of constant effective area.
- 30 5. In a charge forming device having an induction passage including a portion of constant effective area, a large and a small venturi arranged concentrically relative to each other and disposed within said portion of the induction passage, a throttle barrel having its axis offset relative to said venturis, and means to discharge fuel into the small venturi.
- 35 6. In a charge forming device including an induction passage having a section of constant effective area, a primary venturi, a secondary venturi concentric thereto, and a mixture chamber offset relative to the venturis, said venturis being disposed within said section of the induction passage.
- 40 7. In a charge forming device having an induction passage including a large and a small venturi and a mixture chamber, the large venturi being offset with respect to at least one of the other parts of the induction passage, said induction passage having a portion of constant effective area within which the venturis are disposed.
